UNITED STATES PATENT OFFICE.

BERNARD GALLAGHER, OF LYNN, MASSACHUSETTS.

CANNON.

1,101,841.

Specification of Letters Patent. Patented June 30, 1914.

Application filed March 1, 1913. Serial No. 751,438.

To all whom it may concern:

Be it known that I, BERNARD GALLAGHER, a citizen of the United States, residing at Lynn, in the county of Essex and State of 5 Massachusetts, have invented certain new and useful Improvements in Cannon; and I do hereby declare the following to be a full, clear, and exact description of the invention, such as will enable others skilled in the art 10 to which it appertains to make and use the same.

The present invention relates to cannon, and more particularly to a smooth bore 15 cannon provided with mechanism for rotating the projectile when the cannon is discharged.

The object of the present invention is to provide a smooth bore cannon with mechanism for rotating the projectile.

20 With the above object in view, the present invention consists in the improvements in cannon hereinafter described and particularly pointed out in the claims.

In the drawings which illustrate the preferred embodiment of the present invention, 25 Figure 1 is a side elevation of the cannon; Fig. 2 is a section taken on the line 2—2 of Fig. 1; Fig. 3 is a longitudinal section showing a modification; and Fig. 4 is a section 30 taken on the line 4—4 of Fig. 3.

Referring to Figs. 1 and 2 of the drawings, the cannon body has a smooth bored barrel 2 with a powder chamber 3 behind the projectile 4. The projectile 4 has a number of ratchet-like teeth 5 formed around its periphery. These teeth are arranged to be engaged by a movable striker or pawl 6 located in a recess 7 in the face of the cannon bore. The striker 6 is mounted upon the 35 end of a piston rod 10 which extends from a cylinder 11 through a sliding bearing 12 into the recess 7. The piston rod 10 is surrounded by a helical spring 13 which serves to normally maintain the piston 14 at the outer 40 end of the cylinder 11. In order to move the striker 6 to the right, as viewed in Fig. 2, and to thereby impart a rotary motion to the projectile 4, a connecting passage 17 connects the outer end of the cylinder 11 and the powder chamber 3. When the charge 45 of powder is ignited, the burned gases from the powder chamber 3 rush through the connecting passage 17 and force the piston 14 to the right, as viewed in Fig. 2, causing the 50 striker 6 to rotate the projectile 4. The

pressure of the burned gases in the powder chamber also, at the same time, drives the projectile forward so that the rotary movement is imparted to it as it starts forward after the ignition of the powder charge, and 60 thus the projectile has a rotary movement when it is discharged.

Referring to Figs. 3 and 4 of the drawings, which show a modification of the structure shown in Figs. 1 and 2, the cannon body 65 has a smooth bored barrel 2 with a powder chamber 3 behind the projectile 4. Projecting forward from the breach block 20 and through the powder chamber 3 is a triangular bar 21. The forward end of the 70 bar is twisted to form a steep screw thread 22 which is adapted to enter a screw-threaded cavity 23 in the projectile 4. When the charge of powder in the powder chamber 3 is ignited, the projectile 4 is moved forwardly, and, since it has a threaded connection with the twisted bar 21, imparts a rotary movement to the projectile 4 as it moves forward after the ignition of the powder charge. 80

While the preferred embodiment of the present invention has been specifically illustrated and described, it is to be understood that the present invention is not limited to the preferred construction, but may be embodied in other constructions within the purview of the present invention as set forth in the following claims:— 85

1. A smooth bore cannon having, in combination, a cannon body having a smooth 90 bored barrel through which the projectile is discharged and a powder chamber behind the projectile, and mechanical means mounted on the cannon body having a connection with the projectile before ignition of the 95 powder charge and operating after the ignition of the powder charge under the influence of the gas pressure thus generated to cause a rotary movement to be imparted to the projectile as it moves forward in the 100 smooth bore of the barrel.

2. A smooth bore cannon having, in combination, a cannon body having a smooth 105 bored barrel through which the projectile is discharged and the powder chamber behind the projectile, and mechanism having a separate passage leading to the powder chamber and operated by the pressure of the burned gases therein passing through said passage for engaging the projectile and im- 110

parting to it a rotary movement independently of its forward movement when the charge of powder is ignited.

3. A smooth bore cannon and projectile therefor having, in combination, a cannon body having a smooth bored barrel through which the projectile is discharged and a powder chamber behind the projectile, a projectile and a tooth formed on the outside of the projectile, a striker mounted on the

cannon body to engage the tooth on the projectile, and mechanism operated by the pressure of the burned gases in the powder chamber for moving the striker against the tooth on the projectile to rotate the projectile when the powder charge is ignited.

BERNARD GALLAGHER.
